(57) **CLAIM**

The ornamental design for a satchel, as shown and described.

DESCRIPTION

Figure 1.1 is a front elevational view of the satchel, showing my new design;

Figure 1.2 is a right front perspective view thereof;

Figure 1.3 is a rear elevational view thereof;

Figure 1.4 is a top perspective view thereof; and

Figure 1.5 is left rear perspective view thereof.

The broken lines in the figures depict stitching that forms no part of the claimed design.
